[57] CLAIM

The ornamental design for handle of the screwdriver, as shown and described.

DESCRIPTION

FIG. 1 is a perspective view of handle of the screwdriver showing my new design;

FIG. 2 is a front elevational view thereof; with the rear side being a mirror image of that shown;

FIG. 3 is a left side elevational view thereof; with the right side being a mirror image of that shown;

FIG. 4 is a top side elevational view thereof;

FIG. 5 is a bottom side elevational view thereof; and,

FIG. 6 is a perspective view of my new design.

The broken line showing of the blade in FIG. 6 is for illustrative purposes only and forms no part of the claimed design.
